UNITED STATES PATENT OFFICE.

CHARLES A. LIEB, OF NEW YORK, N. Y.

FIRE-ESCAPE AND WATER-TOWER COMBINED.

SPECIFICATION forming part of Letters Patent No. 316,375, dated April 21, 1885.

Application filed February 28, 1885. (No model.)

To all whom it may concern:

Be it known that I, CHARLES A. LIEB, a citizen of the United States, residing at New York, in the county and State of New York, 5 have invented new and useful Improvements in Fire-Escape and Water-Tower, of which the following is a specification.

This invention consists of an improved fire-escape and water-tower, the platform of which 10 is supported upon a tube which is arranged to slide in suitable guides, and is forced upward along with the platform by the agency of a hydraulic ram. The water for operating the ram is forced through a pipe or hose 15 connected with the platform of the tower, and is conducted through a valve into the lifting-tube of the ram. One of the sides of the valve-chamber is provided with an opening that connects with a discharge pipe or nozzle for throwing 20 water onto a fire from the top of the platform. The platform can be rotated to face in any direction by means of gearing operated from the platform. The apparatus is mounted on wheels whose axles are secured to a suitable 25 wagon frame or body, so that the apparatus can be drawn like any conveyance to the place where it is to be used. It is essential that the apparatus stand level when in use, and in order to obtain this position when the surface of 30 the street or place where it is to be used is not level I provide feet, which in this example are four in number, and which extend downward from swinging arms that turn on corners of the wagon-body. These feet contain 35 sliding tubes, each of which is forced downward through suitable guides by the agency of a hydraulic ram, the quantity of water forced into each being regulated automatically by 40 means of a leveling device which is connected with the feet by pipes running along the swinging arms. The several pipes lead from separate valve-passages in the chamber of the leveling device, the valves being opened 45 by the oscillations of the device when the apparatus is not level, so as to allow the water to pass into the appropriate pipes and cause the feet connected therewith to be extended, so as to bring the apparatus to the 50 proper level. In this manner the water, acting on the tubes of the feet after the manner

of a hydraulic ram, is made to bring the wagon-body to a true level through the agency of the automatic leveling device.

This invention is illustrated in the accompanying drawings, in which Figure 1 is an elevation, partly in section, of my improvement. Fig. 2 is a section in the line *xx*, Fig. 1. Fig. 3 is a plan view of the platform. Fig. 4 is a horizontal section through the leveling device in the line *yy*, Fig. 5, the observer being supposed to look upward in the direction of the arrow. Fig. 5 is a vertical section of the leveling device.

Similar letters indicate corresponding parts. 65

The letter A designates the tower-platform. It is extensible, being composed of divisions that can slide upon each other, as indicated in Fig. 3. In Fig. 1 it is shown in cross-section. The platform turns on a pivot, *p*, projecting 70 from a toothed disk, C. The disk is fastened to the top of the lifting-tube B of the ram, and moves up and down with said tube. A pinion, D, whose shaft extends upward through the platform, meshes into said disk C, and 75 serves to turn the platform upon the supporting-tube and the disk C horizontally in different directions, the shaft of the pinion being provided with a hand-wheel, E, for that purpose. 80

The top of the tube B² is closed by the disk C, on which is secured the valve F, through which the water is supplied to the lifting-tube B. The chamber of valve F is provided with an opening and hose or pipe, G, which may be 85 used against a fire from the top of the platform, and which may be closed by the stop-cock H.

The water to be used in connection with the apparatus is supplied through a pipe or hose, J, which connects with a fire-engine or other force-pump, and when the valve F is opened by turning the hand-wheel I (the stop-cock H being closed) the water is forced through valve F into the lifting-tube B. The water-tube B slides in the water-tube B', and the bottom of the latter is secured to the bottom plate, *f*. 90

From the bottom of the fixed water-tube B' and through the plate *f* a pipe, K, extends, 100 which pipe supplies the water to the device for leveling the structure, which in this ex-

ample of my invention consists of a pendulum-valve and chamber. The pipe K extends to the leveling device, and is provided with a two-way cock, L, situated at the lowest part 5 of the pipe, one of its ways permitting the water to be forced onward toward the leveling device, and the other discharging the water to the ground from the pipe K and from the tubes B and B'. The pipe K, between the 10 two-way cock and the leveling device, is provided with a stop-cock, M, which is closed when the apparatus has been brought to a horizontal position. The water which is forced through the tubes B B' and pipe K is conducted by the latter into the water-way N of the 15 valve-chamber O of the leveling device, which is provided with valves P, that close valve-passages R, communicating between the water-way N and a series of pipes, S, leading from the valve-chamber O through the swinging 20 arms T into the sliding tubes U of the extensible water-feet V. There are two tubes, U, in each foot V, the inner one sliding in the other, being forced downward and outward by the 25 pressure of the water acting upon it on the principle of the hydraulic ram. This action takes place with the feet V of that part of the wagon body or structure which is lower than the other parts, because the position which 30 will be taken by the pendulum under these circumstances will open that one or those of the valves P which are connected with the lowest feet, and will keep the same open until each foot becomes extended to the ground, 35 and by the extension of its tube raises its part or corner of the wagon-body to the proper level, so that the pendulum reaches a vertical position with reference to the wagon-body and the chamber O.

40 The tubes of the feet V may be made pointed at their lower ends, so as not to slip on the ground, and near their extremities they are provided with discharge-cocks W, by which the water in the tubes and in the pipes S may be discharged when the apparatus is taken 45 out of action.

The pendulum Y swings from a ball-and-socket joint, Z, arranged in the central upper part of its valve-chamber, and the pendulum-rod has on it an enlargement, a, where it passes 50 through the valve-chamber, against which the inner ends of the valve-stems of the valves P rest, being held against it by the pressure of the water in the annular water-way N against the valves. It follows from this construction 55 that the swing of the pendulum, or rather the departure of the valve-chamber O from a true horizontal position, will cause one or more of the valves to be opened and the water to be forced through the corresponding pipes, S, and into the tubes of the corresponding feet, when the inner tubes will be forced out by the 60 pressure of the water.

All the valves P can be opened, when desired, by screwing up the conical sleeve b, 65 which surrounds the enlargement a of the pendulum-rod, so as to force it up between

said enlargement and the ends of the valve-stems, and when this is done the water can be discharged from the chamber by opening the 70 cock c.

The swinging arms T consist of frames supported and turning in the corner of the wagon frame or structure. The pipes S are suitably packed at the joint d, where they enter the 75 shafts of the arms, and the arrangement is such that the flow of water through the pipes S is not interrupted by the swinging of the arms.

The water-tubes B B' are combined with tubes B² B³ in the manner shown in Fig. 1. 80 The outer tube, B³, is secured to the frame of the wagon or structure by a ring, e, or other suitable means, and its lower end is fixed to the plate f, which also carries the fixed water-tube B'. The outer tube, B³, serves as a guide 85 to the tube B², which, like the lifting-tube B, is secured to the toothed disk C.

The passage-way of the valve F, through which water is forced into the tube B, is provided at its lower end with a check-valve, g. 90

In arranging the apparatus for use the stop-cock H of the hose-pipe G is closed, and the valve F is opened, so as to cause the water to enter the tube B and to pass into pipe K, the stop-cock M being opened and the two-way 95 cock turned in the proper direction to conduct the water through the pipe. The water passes from the pipe K into the chamber O, whence it is distributed in the manner above mentioned, as may be required to bring the apparatus to a level position. When this has been accomplished, the stop-cock M is closed, and the force of the water is exerted in the tubes B B' on the principle of the hydraulic ram, so as to force the tube B upward, bearing with 100 it the platform. When the desired elevation has been reached, the valve F is closed, and the water in the tube B is retained, and the elevation of the tube and tower maintained by means of the check-valve g, which prevents 105 the escape of the water, and consequent lowering of the platform. In order, now, to use the stream of water forced through the hose I against the fire, the stop-cock H is opened and the water allowed to pass into the pipe G, 110 the platform being turned in the proper direction by operating the pinion D.

The extensible platform is made with divisions 1 2 3 4, which slide upon each other, so that the platform can be extended to an equal extent in both directions from the toothed disk C as a center. The division 4 is here shown as only partly extended. This capacity of the platform for extension increases its usefulness, as it enables the firemen to be at a safe 115 distance from a fierce fire, and yet to be at the proper elevation for efficient work. The equal divisions of the platform at the opposite ends serve to balance each other.

The extension of the platform can be effected by any suitable means.

When it is desired to lower the platform, the two-way cock L is opened, so as to permit the water in the tube B to escape, thereby

causing the platform to fall gradually as the water is allowed to escape.

It is evident that the apparatus can be used also as a fire-escape by elevating the tower at 5 the place of peril and receiving upon the platform those who are in danger.

The swinging arms are arranged so as to lie close against the sides of the wagon when the latter is in motion, and when they are used 10 for bringing the wagon to a level condition they are swung out to such positions as will secure the requisite stability.

In practice the tube B will be of less diameter in comparison with the other tubes than 15 is here shown.

I do not wish to limit myself in the number of the tubes to be used either for lifting the platform or for placing the wagon in a level position, as there may be several series of 20 tubes sliding on each other in the manner commonly employed in the telescopic arrangement of tubes.

Other automatic devices acting by gravity 25 can be employed instead of the pendulum-valve here shown for leveling the apparatus without departing from my invention, which, in this feature of it, includes the use of gravity in connection with the valves and pipes of the leveling apparatus for securing automatically 30 the leveling of the wagon or structure at the place where it is to be used.

I do not confine myself to the use of a column of water in carrying out my invention, as any liquid or fluid under pressure can be 35 employed.

What I claim as new, and desire to secure by Letters Patent, is—

1. The combination, with a wagon-frame or other structure, of the automatic leveling device above described and the feet V, constructed and arranged so as to be extended by 40

the pressure of a column of water on the principle of the hydraulic ram, substantially as above described.

2. The combination of the automatic leveling device, the pipes S, arms T, and the extensible feet V, operated by the pressure of a column of liquid or fluid, substantially as described.

3. The combination of the outer stationary tube, B³, the interior stationary tube, B', the fluid-tube B, sliding vertically within the interior tube, the valve F at the upper end of the said fluid-tube, the fluid-supply pipe J, the hose-pipe G, and the platform A, substantially as described.

4. The combination of the tubes B B', arranged to be moved one upon the other by fluid-pressure, the platform A, the valve F, the supply-pipe J, the pipe K, connecting 60 with the tubes, the automatic leveling device, substantially as described, the feet V, and the wagon frame or structure, essentially as set forth.

5. The combination of the valve-chamber 65 O, the valve P, the sleeve b, for opening the valves, and the pendulum Y, with the wagon frame or structure, the sliding feet V, and pipes connecting the valve-chamber with the feet for leveling the wagon frame or structure, 70 substantially as described.

6. The sleeve b, in combination with the pendulum Y and the valves P of the pendulum-valve, substantially as described.

In testimony whereof I have hereunto set 75 hand and seal in the presence of two subscribing witnesses.
